C. F. BACKMYER,
GARMENT FASTENER.
APPLICATION FILED OCT. 15, 1915.

1,216,263.

Patented Feb. 20, 1917.

UNITED STATES PATENT OFFICE.

CHRISTOPHER F. BACKMYER, OF CHICAGO, ILLINOIS.

GARMENT-FASTENER.

1,216,263.

Specification of Letters Patent. Patented Feb. 20, 1917.

Application filed October 15, 1915. Serial No. 55,992.

To all whom it may concern:

Be it known that I, CHRISTOPHER F. BACKMYER, a citizen of the United States, and a resident of the city of Chicago, in the county 5 of Cook and State of Illinois, have invented a certain new and useful Improvement in Garment-Fasteners; and I do hereby declare that the following description of my said invention, taken in connection with the accompanying sheet of drawings, forms a full, clear, and exact specification, which will enable others skilled in the art to which it appertains to make and use the same.

My invention relates generally to improvements in garment fasteners, and it consists, essentially, in the novel and peculiar combination of parts and details of construction, as hereinafter first fully set forth and described and then pointed out in the claims.

20 In the drawing already referred to, which illustrates the details of my invention more fully, Figure 1 discloses the blank of the eye member of my invention partially formed to proper shape, and it is now to be stated that 25 this blank is made from relatively springy sheet metallic material, such as brass, German silver, or cold rolled steel. Fig. 2 is a bottom plan of said blank in its finished condition. Fig. 3 is a bottom plan of the stud 30 member of my invention, and Fig. 4 is a cross section thereof in line 4—4 of Fig. 3. Fig. 5 is a cross section of the eye and the stud member in partial assembly, and Fig. 6 is a like section showing the said parts in 35 completely assembled condition. Fig. 7 is a bottom plan of a slightly modified form of eye member, and Fig. 8, a section thereof in line 8—8 of Fig. 7.

Like parts are indicated by corresponding 40 symbols or characters of reference in all the figures of the drawing.

The aim of this invention is the production of a fastener for the overlapping edges or seams of dresses, coats, waists and other 45 garments in which the disadvantages of the typical hook and eye are eliminated. Among these disadvantages may be named the liability of the hooks and eyes becoming disengaged from each other whereby the flap 50 or seam of the garment becomes loosened and presents an unsightly appearance.

Another result aimed at in this invention is to construct a garment fastener, the elements of which are so flat and so shaped 55 that when the garment to which the fas-

tener is attached is being passed through a wash wringer or is being ironed whether by a mangle or by hand, there will be no tendency to distort the parts of the fastener and destroy the usefulness or efficiency thereof, 60 as is now the case with the usual type of hook and eyes.

The eye member of my invention is preferably produced from a substantially disk-like blank A, having projecting tongues B 65 and B' projecting from diametrically opposite margins of said blank, the latter of which is much shorter than the former. Concentrically of this blank there is a raised flat portion B'', which portion has a slot C, 70 terminating in an enlarged opening C', the enlarged opening being off the center of the disk A.

It is now to be stated that the margin 10 of the blank A is curled under said blank A 75 in a direction opposite the flat, raised portion B'' to produce a neat and rounding finish. The projecting tongue B is also bent under the blank A, passing directly underneath the slot C and enlarged opening C', 80 and the tongue B' is likewise bent back under said blank and underneath said tongue B to support the free end of the latter.

In the upper face of said tongue B, substantially axially beneath the enlarged opening C' of the raised portion B'' is provided 85 a depression D and directly under the slot C, practically medially of the length thereof, there is formed in said tongue a similar depression D', the two depressions being 90 separated by a bridge wall D''.

The stud member E of my device is disk like in contour and is possessed of a raised marginal bead 20 and a sunk, concentric, flat faced depression 21, centrally from which 95 extends a stud 22, having an enlarged head 23, the exterior contour of which head is of the same shape as the depressions D and D' of the tongue B.

In assembling the eye and stud member of 100 my invention, the stud 22 and its head 23 is first passed through the enlarged opening C' of the eye member, and it will be observed that when the head 23 is in engagement with the depression D of the tongue B the flat 105 faces B'' and 21 of the eye and stud member are in facial contact, thereby preventing downward pressure upon the tongue B. The stud member E is now forcibly moved so that the stud 22 will enter the slot C and the 110

- head 23 caused to depress the bridge wall D'', after which the said head 23 becomes lodged in the depression D', whereon the inherent spring in the tongue B forces the said head 23 upwardly until the under side 24 thereof contacts against the underside of the raised depression B'' surrounding the slot C, thereby maintaining said stud member in locked connection with said eye member.
- 10 Between the margins 10 and 20 and the concentric flattened portions B'' and 21 of the eye member A and stud member E are provided concentrically arranged apertures 30 and 31, respectively, wherethrough thread 15 may be passed to secure said members to the parts of the garments to be removably fastened together by my invention.

In Figs. 7 and 8 I indicate a slight modification of my invention. In this instance I dispense with the tongues B and B' and fix in place between the curled margin 10 of the disk A, a circular, thin, sheet metallic plate M. This plate M performs the same functions as the tongue B and is possessed of the same depressions D and D' and the bridge wall D'' as are provided in the tongue B.

I have hereinbefore disclosed the preferred mode of practising my invention, but I reserve the right to make such and any changes as might occur to one skilled in the art to which this invention appertains, or to make any and all such alterations as may

be permitted under the doctrine of equivalents.

Having thus fully described my invention 35 I claim as new, and desire to secure to myself by Letters Patent of the United States:—

1. An eye-member for a garment or similar fastener, comprising a circular disk, said disk having its marginal edges undeturned, 40 there being in said disk an annular, raised, flat, portion, there being in said flat portion a slot, said slot terminating in an enlarged opening, and a member underneath said circular disk, said member having a depression 45 in its face directly below said enlarged opening, and a further depression adjacent to the first-named depression, directly below said slot, there being a bridge-wall between the two depressions, said member being resilient. 50
2. An article of the class described comprising a disk like member having a slot terminating in an enlarged opening, and a tongue integrally formed with said member, bent back under said member, and having the 55 free end of said tongue supported by said member, said tongue having a depression in its upper face directly below said enlarged opening and another depression in its upper face directly under said slot, and a bridge 60 wall between said depressions.

In testimony that I claim the foregoing as my invention, I have hereunto set my hand.

CHRISTOPHER F. BACKMYER.
